United States Patent Office

Des. 228,177
Patented Aug. 21, 1973

228,177

SNAP-ON PANELING OR SIMILAR ARTICLE

Joseph N. LaBorde, Baton Rouge, La., assignor to Ethyl Corporation, Richmond, Va.

Filed Dec. 22, 1971, Ser. No. 211,154

Term of patent 14 years

Int. Cl. D25—01

U.S. Cl. D13—1 J

FIG. 1.

FIG. 2.

FIG. 1 is a perspective view of a snap-on paneling or similar article embodying my new design, and

FIG. 2 is a sectional view taken along line 2—2 of FIG. 1.

I claim:

The ornamental design for a snap-on paneling or similar article, substantially as shown.
